SPOON

Irving Harper, New York, N. Y., assignor to Chas. D. Briddell, Inc., Crisfield, Md., a corporation of Maryland

Application October 8, 1954, Serial No. 32,605

Term of patent 14 years

(Cl. D44—29)

Fig. 1 is a side elevational view of a spoon showing my new design.

Fig. 2 is a top plan view thereof.

Fig. 3 is a cross-sectional view taken on line 3—3 of Fig. 1.

Fig. 4 is a cross-sectional view taken on line 4—4 of Fig. 2.

I claim:

The ornamental design for a spoon, as shown.
